STOCKING

Ralph J. Schwarz, New York, N. Y., assignor to Sapphire Hosiery Corporation, New York, N. Y., a corporation of Delaware

Application June 9, 1950, Serial No. 10,443

Term of patent 14 years

(Cl. D47—7)

To all whom it may concern:

Be it known that I, Ralph J. Schwarz, a citizen of the United States, residing at New York city, in the county of New York and State of New York, have invented a new, original, and ornamental Design for a Stocking, of which the following is a specification, reference being had to the accompanying drawing, forming part thereof.

In the drawing

Fig. 1 is a side view of a stocking showing my new design;

Fig. 2 is a side view of the stocking, with the top part broken away;

Fig. 3 is a rear view of the stocking, with the top part broken away; and

Fig. 4 is a bottom plan view of the stocking.

I claim:

The ornamental design for a stocking, substantially as shown.

RALPH J. SCHWARZ.
